UNITED STATES PATENT OFFICE

GEORGE L. DANFORTH, JR., OF CHICAGO, ILLINOIS, ASSIGNOR, BY MESNE ASSIGNMENTS, TO OPEN HEARTH COMBUSTION COMPANY, OF CHICAGO, ILLINOIS, A CORPORATION OF DELAWARE

OPEN-HEARTH-FURNACE PORT

Application filed July 10, 1922. Serial No. 573,867.

This invention relates to a new and improved open hearth port construction and more particularly to the construction of such ports and their associate passages and dampers for controlling flow from the ports to the furnace chamber.

As is well known in the art, open hearth furnaces are double ended and are reversed in operation, each end serving alternately to introduce the fuel and air and to carry off the products of combustion. The products of combustion largely exceed in volume the incoming air and fuel and consequently the ports must be designed with a view of carrying off the larger volume of the products of combustion. It is, however, necessary for efficient operation that the incoming air and fuel be properly intermingled and controlled to form a relatively short, hot flame properly directed upon the bath of metal in the furnace.

Certain furnaces have been designed with damper controlled ports upon each end of the furnace, these ports being closed off upon the incoming end and serving on the outgoing end to aid in carrying off the products of combustion. A furnace of this type is shown in the patent to McKune, No. 1,339,855, dated May 11, 1920. In these furnaces, two dampers are required, one in each of the supplemental discharge passages, and these dampers not only complicate the installation but due to their water-cooling, involve considerable heat losses.

It is desirable in open hearth furnaces to separate the incoming fuel at each end of the furnace into a plurality of small streams since the small streams will more readily mix with the air and will give a more rapid combustion. Another advantage of divided streams lies in their greater efficiency in melting down a charge. A single central flame will be broken up by impinging upon the charge and will be deflected to the walls and roof. This results not only in inefficient heating but in damage to the furnace walls and roof. On the other hand the divided streams will meet upon the piled up charge and will efficiently melt it down. In the construction of separate ports the furnace

side walls may be utilized as port walls so that but little additional brickwork is required over a single port furnace.

It is an object of the present invention to provide a new and improved port construction wherein the fuel is introduced in a plurality of streams and wherein the fuel streams are partially surrounded by the air stream. 55

It is an additional object to provide fuel ports located adjacent the side walls of the furnace and the air port located intermediate and above the fuel ports. 60

It is an additional object to provide ports of this character in which the furnace side walls serve to form one side of the fuel ports. 65

It is a further object to provide a construction of this type in which the side walls and roof are inclined inwardly toward the port ends and thereafter inclined outwardly 70 to form an approximate Venturi section.

It is another object to provide in a furnace having a plurality of ports, a centrally located damper between the ports and the furnace proper, the damper being movable 75 into and out of position.

Other and further objects will appear as the description proceeds.

I have shown a preferred embodiment of the invention in the accompanying drawings, 80 in which—

Figure 1 is a vertical section showing one end of a furnace constructed according to the present invention;

Figure 2 is a horizontal section taken on 85 line 2—2 of Figure 1;

Figure 3 is a vertical transverse section taken on line 3—3 of Figure 1; and,

Figure 4 is a vertical transverse section taken on line 4—4 of Figure 2. 90

The furnace comprises the slag pocket 7 from which leads the air uptake 8 opening into the air port 9 located on the center line of the furnace. It will be understood that the slag pocket is connected by usual passages to suitable regenerators in a manner well known in the art. The slag pocket 10 is connected by uptakes 11 and 11' with lateral gas ports 12 and 12'. As shown in the drawings, the several ports are water-cooled by 100

pipes 13. The side wall 14 of the furnace is provided with an inwardly inclined portion 15 located approximately at the discharge opening from ports 9, 12 and 12'.

As clearly shown in Figure 1, the furnace roof 16 slopes downwardly to this point and then upwardly so that the roof together with the sides forms approximately a Venturi section. The damper 17 is provided with the water-cooled frame 18 and is movable upwardly through water-cooled guides 19 into the housing 20.

In the operation of the furnace, upon the incoming end, the fuel gas will be heated in suitable regenerators and led from them to the slag pocket 10. From the slag pocket 10, it will pass through uptakes 11 and 11' to ports 12 and 12'. Each of these ports will thus discharge a stream of gas, the streams being directed inwardly toward the center line of the furnace.

The incoming air is preheated in the usual regenerators and passes through slag pocket 7 to the uptake 8. From the uptake 8 it passes out through air port 9. This port 9 extends between the two gas ports and also above them as shown in Figure 4. Figure 4 also shows clearly how the outer walls of the gas ports are formed by the outer furnace walls.

The damper 17 is lowered to the position in which it is shown in Figure 1 and it thus serves to split the air into two streams which are directed toward the lateral gas streams. This deflection of the air serves to cause it to more rapidly intermingle with the gas and the relatively small passage area between each side of the damper 17 and the adjacent, inwardly inclined portion 15 of the furnace wall forms a relatively restricted port adapted to discharge a short, properly controlled flame. Upon the outgoing end of the furnace, the damper 17 is drawn up into the housing 20 and the full area of the air port 45 and the two gas ports is available to carry off the products of combustion. These products of combustion are led from the slag pocket 7 to the usual regenerator.

But one form of construction under my invention has been shown by way of illustration and it is to be understood that it is capable of various other embodiments such as come within the scope of the appended claims.

6. I claim:

1. In a reversible regenerative furnace, a plurality of separate fuel ports located adjacent the side walls of the furnace, the side walls being inclined inwardly toward the port ends and thereafter inclined outwardly to form an approximate Venturi section, and an air uptake located on a line intermediate said ports.

2. In a reversible regenerative furnace, a plurality of separate fuel ports located ad-

jaacent the side walls of the furnace, the side walls being inclined inwardly toward the port ends and thereafter inclined outwardly and the roof inclined downwardly toward the port ends and thereafter upwardly to form an approximate Venturi section, and an air uptake 70 located on a line intermediate said ports.

3. In a reversible regenerative furnace, a plurality of separate fuel ports, one being located adjacent each side wall of the furnace 75 in each furnace end, the furnace side wall forming one wall of each such port, walls closing the inner sides and tops of said fuel ports and an air port located intermediate the lateral gas ports and extending above 80 such ports.

4. In a reversible regenerative furnace, air and gas ports in the furnace ends, and a damper located centrally in each furnace and between the ports and furnace chamber. 85

5. In a reversible regenerative furnace, air and gas ports in the furnace ends, and a damper located centrally in each furnace and between the ports and furnace chamber, the damper being of less width than the furnace 90 and affording port area upon either side thereof when in its lower position.

6. In a reversible regenerative furnace, lateral ports, a central port, and a damper spaced from said ports and movable into position in 95 front of said central port to deflect flow therethrough toward the flow from the side ports.

7. In a reversible regenerative furnace, lateral gas ports, a central air port, and a damper movable in front of the air port to deflect the 100 air stream into the lateral gas streams.

8. In a reversible regenerative furnace, air and gas ports in the furnace ends, and a damper located centrally in each furnace and between the ports and furnace chamber, and means adapted to move the damper vertically 105 through the roof of the furnace.

9. In a regenerative furnace having an air port and a gas port at each end thereof, the gas port extending on an angle to the air 110 port so as to discharge gas across the flow of air from the air port, slide valves for controlling the outlet passage of said air ports.

Signed at Chicago, Illinois, this 6th day of July, 1922.

GEORGE L. DANFORTH, Jr.
